SELF-CLOSING BOTTLE

Arthur S. Odin, Detroit, Mich., assignor of five
per cent to Julius C. Pliskow, Detroit, Mich.

Application November 27, 1942, Serial No. 467,137

1 Claim. (Cl. 215—60)

This invention relates to new and useful improvements in bottles and other containers, and more particularly to a self-closure therefor.

The principal object of the present invention is to provide a bottle structure having a neck in which a closure element is free to close the bottle when liquid is not being poured therefrom, or moved to an out-of-the-way position when liquid is being poured.

Another important object of the invention is to provide a self-closing bottle in which the closing element is primarily employed for sealing the bottle before primary use.

Other objects and advantages of the invention will become apparent to the reader of the following description.

In the drawing:

Figure 1 represents a vertical sectional view through a bottle constructed in accordance with the present invention and being the form which is employed for gaseous liquid containing bottles.

Figure 2 is a section on line 2—2 of Figure 1.

Figure 3 is a fragmentary vertical sectional view through a slightly modified form of the invention, the closure being especially adapted for non-gaseous liquids.

Referring to the drawing wherein like numerals designate like parts, it can be seen in Figure 1 that numeral 5 represents the body of a bottle constructed in accordance with the present invention. This bottle has an upwardly tapering neck 6 which is constricted, as at 7, where it merges with the shoulder of the bottle to define a seat 8.

Just above the seat 8 the neck 6 is formed with an internal circumferentially extending rib 9.

At the upper end of the neck 6 is an internal circumferentially extending groove 10 for receiving the peripheral portion of a rubber or other resilient washer 11 into which can seat a ball 12 of glass or some other suitable material. The single washer 11 and ball 12 type of seal is employed with gaseous liquids, the gas pressure of the liquid serving to hold the ball 12 in sealing position against the washer 11. A supplemental cover or seal 13 may be provided for the upper end of the neck 6 to prevent dust from accumulating on the washer 11 and ball 12.

In the use of this form of the invention, the cover 13 is first removed and then the ball 12 is forced downwardly, allowing the pressure to escape. The ball 12 will settle to a seated position on the seat 8.

When the bottle is tipped to a pouring position, the ball will rest between the constricted portion 7 and the rib 9 so as to be out of the way of the pouring liquid. When the bottle is again righted, the ball will again seat upon the seat 8, thus preventing the escape of gas from the liquid and thereby preserving the liquid fresh over an appreciable period of time.

A modification of the invention is shown in Figure 3 and is intended for non-gaseous liquids. In this form of the invention, two washers 11a, 11a are disposed in grooves 10a, 10a at the inner side of a bottle neck 6a, these washers 11a, 11a being in close spaced relation, with a spherical closing element 12a interposed between the same. In other words, pressure does not hold this closing element 12a in position, it being held in position by the two washers in substantially the manner shown in Figure 3.

10 However, when the ball 12a is forced downwardly away from the washers 11a, 11a, it will drop to a seat 8a where it will subsequently function as in the instance of the closure element 12.

15 While the foregoing specification sets forth the invention in specific terms, it is to be understood that numerous changes in the shape, size and materials may be resorted to without departing from the spirit and scope of the invention as claimed hereinafter.

20 Having described the invention, what is claimed as new is:

25 A bottle having an elongated tubular neck of circular cross section from end to end and tapering smaller upwardly, said neck having an annular constriction of symmetrical form at its lower end defining an annular internal valve seat, and being formed with an annular internal circumferentially extending rib above said seat, a resilient washer secured in the upper end of said neck, and a spherical closure element normally seated upwardly against the washer to close its opening, said closure element being releasable from the washer so as to fall onto and close the bottle at said seat when the bottle is upright, the rib acting to stop outward movement of ball from said seat at a point outwardly of the latter and inwardly of the washer to permit pouring of the contents from the bottle when the latter is tipped in any direction to a pouring position.

ARTHUR S. ODIN.
